LOOP INPUT SYSTEM FOR RADIO RECEIVERS

George L. Beers, Haddonfield, N. J., assignor to
Radio Corporation of America, a corporation
of Delaware

Application January 28, 1943, Serial No. 473,806

14 Claims. (Cl. 250—20)

The present invention relates to a loop input system for radio receivers, and more particularly to a loop input system utilizing a permeability tuned auto-transformer.

The use of permeability tuning in the design of broadcast and other receivers has become widespread in recent years due to low cost, compactness, freedom from acoustic feed-back howl and other considerations, such as the lack of suitable materials for the manufacture of variable capacitors. Although this method of tuning is best adapted for use with a capacity antenna device, such as a rod, or a capacity plate, capacity antenna devices are not commercially acceptable due to body capacity effects, the appearance of the rod extending beyond the receiver, and to the extreme insensitivity in shielded buildings. It is therefore desirable to be able to use a loop antenna in conjunction with a permeability tuned input circuit for receivers.

With the advent of permeability tuning systems there arose the need for an efficient loop circuit that would be adapted for permeability tuning. Several loop antenna circuits employing permeability tuning have been devised but they were found to be inefficient in that they have a considerably lower sensitivity than a capacitor-tuned high quality loop. In one instance, there has been used a series variable inductance to tune the loop antenna and a series capacitor which serves to tune the loop below the band to be received.

The average sensitivity of prior art serially connected permeability tuned loop antenna circuits is of the order of 10% of that of a variable capacitor tuned loop input circuit. The improved circuit according to the present invention has a sensitivity of approximately 40% of that obtainable from the same loop antenna, capacitively tuned.

According to the invention the loop input system involves the use of a loop antenna which is suitably tapped onto a variable permeability tuned inductance in the input circuit of a receiver to provide a substantially uniform response across the broadcast or other tuning band and to secure an appreciable increase in sensitivity for a permeability tuned loop circuit over that which is possible with the usual series tuned loop circuit using permeability tuning.

It is therefore one of the objects of the invention to provide an efficient means of using a loop antenna in conjunction with a permeability tuning system.

Another object is to provide efficient coupling

means between the loop antenna and the permeability tuning system of a receiver which will result in a substantially uniform response over the broadcast or other tuning band.

5 A further object of the invention is to secure an appreciable increase in sensitivity for a permeability tuned loop circuit over that which is possible with tuned loop circuits known in the art.

10 The invention will be further understood from the following description, when considered in connection with the accompanying drawings and its scope is pointed out in the appended claims.

In the drawings,

15 Fig. 1 shows the basic circuit involving the invention;

Fig. 2 shows the equivalent T coupling arrangement used in Fig. 1; and

15 Figs. 3, 4 and 5 are curves which will serve to 20 explain the invention.

Referring now to Fig. 1, there is represented at 1 a loop antenna having a suitable number of turns, with one end of the loop directly connected to ground while the other or high potential end is tapped onto a permeability tuned inductance coil 2. As will be shown hereinafter the tapping point is preferably between 25 to 35% of the coil turns from the ground end. The coil 2 and a shunt capacitor 3 constitute the input circuit for 25 coupling to the signal grid of a tube 4 which may be either the first radio frequency amplifier or the detector-oscillator tube of a conventional receiver. A powdered iron core 5 movably mounted within and entering at the ground end of coil 2 serves to tune the input circuit to the signal 30 frequency desired to be received.

The manner in which the permeability tuned circuit of the invention operates is as follows: As the core 5 is caused to move into the L₁ end 35 of the coil and progressively through the entire coil 2 to tune the circuit throughout the desired tuning range, the relative values of the inductances L₁ and L₂ and the mutual inductance M therebetween are continuously varied in such a 40 way to maintain a substantially uniform transfer of voltage from the loop to the grid of tube 4. In other words, as the input circuit is tuned throughout the frequency range, the point to which the loop is tapped is in effect simultaneously varied, 45 the tapping point in effect advancing progressively to a point above the actual tap during the initial adjustment of the core (high frequency end of the tuning range) and then receding progressively until it coincides with the actual tap 50 when the core is adjusted to its fully entered posi-

tion with the coil (low frequency end of the tuning range). By reason thereof the coupling between the loop and input circuit is effectively varied throughout the tuning range to effect a uniform transfer of energy.

In one particular embodiment satisfactory results have been obtained with an inductance coil of 360 turns, tapped at 90 turns or 25 percent, and with a loop of approximately 14 turns spaced over an axial length of 6 inches on a frame, approximately 20 by 36 inches for fitting inside of a console cabinet.

In Fig. 2 the circuit of Fig. 1 is shown with the equivalent T network for the permeability tuned auto-transformer. The distributed capacitance of the loop and the tapped portion L_1 is denoted by C, shown dotted. The elements of the primary circuit are isolated to the left of dash line $a-a$. For the loop antenna of inductance L_1 and the auto-transformer utilized in a particular embodiment the maximum equivalent inductance of (L_1-M) and (L_1+M) in parallel was calculated and found to be $96.3\mu h$. Calculation also shows that the primary resonant frequency for the above value of the equivalent inductance was 3.01 mc., a value considerably above the range to be received. For any other position of the core a higher value for the primary resonant frequency will result.

In Figs. 3 to 5 are shown a number of sensitivity curves obtained with coils of different inductance values and with the loop connected to varying tapping points. The ordinate of each curve sheet represents, in percent, the sensitivity of the present permeability tuned loop input system as compared with that of the same loop antenna, capacitively tuned. For the permeability tuned coil 2 in Fig. 1, there were used coils of different inductance, one of which will be identified as "A" and the other as "B." Coil A comprised 260 turns and coil B comprised 360 turns, and both coils were universally wound to the same length ($1\frac{1}{8}$ ") on the same diameter coil form. The tuning core was the same in each case. The inductance of coil B varied from 196.5 to $2043\mu h$ and its Q varied from approximately 70 to 100 across the band. The inductance of coil A, approximately one half of coil B, varied from 94.9 to $990\mu h$, and its Q varied from 85 to 105 over the band.

Fig. 3 shows the effect of changing the L/C ratio of the circuit, coil A having approximately one-half the inductance of coil B. Curves 1 and 2 are both for a large (i. e., area = 0.334 m^2) 14 turn loop connected to a 25% of the turns tap on coils A and B, respectively. Curves 3 and 4 are for the same loop connected to the 50% of the turns tap on coils A and B, respectively. Thus, a 2 to 1 decrease in L/C ratio causes only a small change in tuning range and a decrease in sensitivity at the high end of the band. An explanation of the effect of the two different tapping points will be deferred until the curves of Fig. 5 are explained.

The effect of increasing the loop turns from 14 to 20 for the case of coil B tapped at the 25% point is shown in Fig. 4. Curve 2 is the same as curve 2 in Fig. 3 for the 14 turn loop, and curve 5 is for the 20 turn loop. A slight increase in tuning range and a small decrease in sensitivity is seen to result from the larger number of turns.

The curves of Fig. 5 show two important effects due to connecting the loop to various tapping points. First, the tapping point on coil A was varied from $6\frac{1}{4}$ to 50 percent. A tap below 25%

results in poor sensitivity. The 25% tap permits a satisfactory tuning range, and at the same time results in practically optimum sensitivity at the high frequency end of the band. The 50% tap results in a greatly reduced tuning range and in lower sensitivity at the high frequency end of the band. Second, the importance of inserting the core from the ground side of the coil is shown by curves 9 and 10 where the greatly reduced sensitivity shown by curve 10 is due entirely to inserting the core at the high end of the coil.

While I have shown and described a preferred embodiment of the invention, it will be understood that modifications and changes may be made without departing from the spirit and scope of the invention, as will be understood by those skilled in the art.

What I claim is:

1. In a radio receiver, an input circuit for said receiver having a tuning inductor which is connected to ground at one end, a magnetic core movable in said inductor for tuning the circuit over a frequency range, and a loop antenna connected between a tap on said inductor and ground.

2. In a radio receiver, an input circuit for said receiver having a tuning inductor which is connected to ground at one end, a magnetic core movable in said inductor for tuning the circuit over a frequency range, and a loop antenna having one end connected directly to ground and the other end connected to a point on the inductor which is between 20 and 35 percent of the turns from the ground end of the inductor.

3. In a radio receiver, an input circuit for said receiver having a tuning inductor and a magnetic core movable in said inductor for tuning the circuit over a frequency range, and a loop antenna connected between the ground end of said inductor and a tap on the inductor which is between 20 and 35 percent of the inductor turns from the ground end, said magnetic core entering the ground end of the inductor.

4. In a radio receiver, in combination, a tuning inductor adapted to function as an auto-transformer, a loop antenna connected in shunt to the primary of said auto-transformer and resonating therewith above the frequency range of the receiver, an input circuit including the secondary of the auto-transformer, and a magnetic core movable in the tuning inductor for tuning the input circuit.

5. The combination defined in claim 4 wherein the primary contains from between 25 to 35 percent of the number of turns of the tuning inductor.

6. The combination defined in claim 4 wherein the primary contains from between 25 to 35 percent of the number of turns of the tuning inductor and the magnetic core enters the low potential end of the tuning coil.

7. In a radio receiver, an input circuit including an auto-transformer, a loop antenna connected in shunt across the primary of said transformer, and means for tuning the input circuit throughout its operating range and for varying simultaneously therewith the inductance of the primary and secondary of said transformer and the mutual therebetween so that a uniform transfer of energy is obtained between the loop antenna and the input circuit.

8. In a radio receiver, an input circuit including an auto-transformer, a loop antenna connected in shunt across the primary of said transformer, and means for tuning the input circuit

throughout its operating range and for varying simultaneously therewith the ratio of the primary to secondary inductance so that a uniform transfer of energy is obtained between the loop antenna and the input circuit.

9. In a radio receiver, an input circuit including an auto-transformer, a loop antenna connected in shunt across the primary of said transformer, and a movable magnetic core cooperating with said auto-transformer for tuning the input circuit throughout its operating range and for varying simultaneously therewith the inductance of the primary and secondary of said transformer and the mutual therebetween so that a uniform transfer of energy is obtained between the loop antenna and the input circuit.

10. In a radio receiver, an electron discharge tube, an input circuit including an inductance coil having one end grounded and its other end connected to the signal control grid of said tube, a loop antenna having one end grounded and its other end connected to a tap on said inductance, and means for tuning the input circuit throughout its operating range and for simultaneously effecting a progressive variation in coupling between the loop antenna and the input circuit.

11. In a radio receiver, an electron discharge tube, an input circuit including an inductance coil having one end grounded and its other end connected to the signal control grid of said tube, a loop antenna having one end grounded and its other end connected to a tap on said inductance, and a movable magnetic core cooperating with said inductance coil for tuning the input circuit throughout its operating range and for simultaneously causing a progressive variation

in coupling between the loop antenna and the input circuit to effect thereby a uniform energy transfer from the loop to the signal grid of the tube.

5. 12. An antenna input system for radio receivers comprising a high-frequency auto-transformer, a ferromagnetic core movable relatively thereto, a capacitance effectively in shunt with the secondary of said auto-transformer and forming a secondary resonant circuit tunable by movement of said core to any desired signal within a range of frequencies, an inductive element exposed to said signals and effectively in shunt across the primary of said auto-transformer forming a primary resonant circuit which is tuned by motion of said core to a frequency higher than the frequency of said signal.

10. 13. An antenna input system for radio receivers comprising a high-frequency coil having one end connected to ground and a tap at a point closer to said coil end, a ferromagnetic core movable relatively thereto, a capacitance effectively in shunt with the whole of said coil and forming a secondary resonant circuit tunable by movement of said core to any desired signal within a range of frequencies, an inductive element exposed to said signals and connected between the coil tap and ground and forming with said coil portion a primary resonant circuit which is tuned by motion of said core to a frequency higher than the frequency of said signal.

15. 14. An antenna input system as defined in claim 13 wherein the tap is at a point from between 25 to 35% of the coil turns from the ground end, and the core is entered at the ground end of the coil.

GEORGE L. BEERS.
